LATCHING MECHANISM

Ferdinand R. Eichner, Pontiac, Mich., assignor to General Motors Corporation, Detroit, Mich., a corporation of Delaware

Application July 9, 1953, Serial No. 366,921

6 Claims. (Cl. 292—217)

This invention relates to latching mechanisms and more particularly to a latching mechanism for a compartment closure of buses and the like.

Buses and other passenger vehicles are provided with various compartments such as engine and baggage compartments which include swinging closures having various types of latching mechanisms. Many of these closures are horizontally hinged and the invention is particularly applicable to this type of closure, although it should be realized that it may also be applied to vertically hinged closures. Such closures are usually provided with an external handle for manual actuation of their latching mechanisms and for the raising of the closure to an open position. The closures are provided with suitable releasable hold open devices so that the handle may be released while access is had to the compartment. In one type of closure, it is desirable that the latching mechanism be so set upon manual release of the handle that further manual manipulation of the handle is unnecessary for latching of the closure, i. e., that the latching mechanism is of the self or slam latching type. In another type of closure, it is desirable that the latching mechanism be so set upon manual release of the handle that further manual manipulation of the handle is necessary for latching of the closure, i. e., that the latching mechanism is of the manual or antislam latching type.

An object of the invention is to provide an improved latching mechanism of the slam latching type.

Another object of the invention is to provide an improved latching mechanism of the antislam latching type.

A further object of the invention is to provide a latching mechanism which is adaptable with but minor modification for either slam or antislam latching. Both the slam and the antislam modifications of the invention have the same general arrangement.

Further objects and advantages of the present invention will be apparent from the following description, reference being had to the accompanying drawings wherein a preferred form of the present invention is clearly shown.

In the drawings:

Fig. 1 is a partial front elevation, partially broken away, of a vehicle compartment closure incorporating the latching mechanism of the invention.

Fig. 2 is a horizontal section, taken substantially on the plane indicated by the line 2—2 of Fig. 1, of the latching mechanism.

Fig. 3 is a vertical section, taken substantially on the plane indicated by the line 3—3 of Fig. 1, of a catch of the latching mechanism.

Fig. 4 is a vertical section, taken substantially on the plane indicated by the line 4—4 of Fig. 1, of the operating linkage of the latch mechanism in closure latching position.

Fig. 5 is a vertical section similar to that of Fig. 4 of the antislam modification with the operating linkage in closure preventing range.

Fig. 6 is a vertical section similar to that of Fig. 4

2

of the antislam modification with the operating linkage in closure unlatching position.

Fig. 7 is a partial front elevation, partially broken away, of the operating linkage of the latching mechanism.

Fig. 8 is a horizontal section taken substantially on the plane indicated by the line 8—8 of Fig. 6 of the antislam modification with the operating linkage in closure unlatching position.

Fig. 9 is a vertical section similar to that of Fig. 4 of the slam latching modification with the operating linkage in closure unlatching position.

Fig. 10 is a horizontal section taken substantially on the plane indicated by the line 10—10 of Fig. 9 of the slam latching modification with the operating linkage in closure unlatching position.

Referring now to the drawings in detail, Figs. 1 through

4 and 7 illustrate the latching mechanism common to both antislam and slam latching modifications. A closure 10 is mounted for upward swinging movement in the compartment opening of the vehicle wall panel 12 by a horizontal rubber hinge 14. The compartment casing is formed by upper and lower channels 16 and 18 and side channels 20 and 22, and the closure 10 by an upper channel 24, side channels 26 and 28, side strips 30 and 32, and inner and outer panels 34 and 36. The compartment casing channels carry rubber seals 38, 40 and 42 that engage the inside edges of the closure 10 to cushion the closure and seal the compartment from dirt and moisture. Bolts 44 secure latch catches 46 to either side of the compartment casing. Each latch catch 46 has a cam-like channel 48 and front and rear shoulders 50 and 52. The catches 46 receive the hooked ends 54 of a torsion latch rod 56 horizontally pivoted on the inside of the closure 10 by side straps 58 and by center straps 60 and 62 secured to the closure handle housing 64 by bolts 66. A latch operating handle 68 having inner and outer panels 70 and 72 and a rubber dust flap 74 is horizontally pivoted on the handle housing 64 by a shaft 76 received in spaced ears 78 on the handle and bearings 79 on the housing.

The shaft 76 carries a coil spring 80 having ends that bear against bosses 79' and 81 on the handle and housing to bias the handle towards latched position. An adjustable crank link 82 pivotally connects at its upper end to a shaft 84 journaled in spaced ears 86 of the handle

45 and at its lower end to a crank 88 on the latch rod 56. Referring particularly to Figs. 2, 3 and 4, the rear shoulders 52 of the catches 46 are so related to the hooked ends 54 of the latch rod 56 as to impose torsion in the latch rod 56 when the closure 10 and handle 68 are in

50 the latched position shown. The latching mechanism is releasably retained in latched position by over-centering of the crank link and handle pivot with respect to the crank link and latch rod pivot and handle to closure pivot. A safety latch 90 insures against accidental opening of the closure. The safety latch 90 is concealed behind the handle 68 and includes a latch 92 suitably pivoted to the handle and spring biased for engagement with a catch 94 secured to housing 64 by the bolts 66.

Figs. 5, 6 and 8 illustrate the antislam modification of 60 the latching mechanism, while Figs. 9 and 10 illustrate the slam latching modification of the latching mechanism. The only structural difference between the modifications is in the location of a stop surface 100 on the housing 64. In the antislam latching modification the stop surface 65 100 is so located as to engage the lower end of crank link 82 when the handle is moved to unlatched position to prevent the crank link and latch rod pivot from over-centering with respect to the handle and crank link pivot and latch rod to closure pivot. In the slam latching modification the stop surface 100 is so located as to allow the

70 crank link and latch rod pivot to overcenter.

The antislam latching modification operates in the following manner. The operator inserts his fingers beneath the handle 68 to release the safety catch 90. He thereafter pulls up the handle from the latched position of Figs. 1 through 4 to the unlatched position of Figs. 6 and 8, moving the latch rod ends 54 from behind the catch shoulders 52. The closure 10 is then opened and the handle released whereupon coil spring 80 moves the handle toward latched position, as illustrated by Fig. 5. The spring 80 is preferably strong enough to move the handle to full latched position but it need only move the handle to the intermediate position of Fig. 5 which comprises the boundary of the slam prevention range of the handle. The latch rod ends will engage the front shoulders 50 of the catches to prevent the closure from latching, as shown in Fig. 5, should the operator attempt to slam the closure without moving the handle to unlatched position. For the operator to latch the closure, it is necessary that he raise the handle to unlatched position so that the latch rod ends may enter the channels of the catches and thereafter shut the closure and move the handle to the latched position of Figs. 1 through 4.

The slam latching modification operates in the following manner. The operator raises the handle from the latched position of Fig. 4 to the unlatched position of Figs. 9 and 10. The crank link 82 does not engage the stop surface 100 until the crank link and latch rod pivot overcenters. Upon release of the handle the coil spring 80 maintains the crank link and latch rod pivot overcentered, thereby retaining the handle in the unlatched position of Figs. 9 and 10. The closure may now be slam latched without further manipulation of the handle for the latch rod ends are in proper position for entry in the catch channels 48, and the inertia of the closure will cause camming of the latch rod ends in the catch channels to effect latching and thereby pull the handle 68 to its latched position.

While the preferred embodiment of the invention has been described fully in order to explain the principles of the invention, it is to be understood that modifications in structure may be made by the exercise of skill in the art within the scope of the invention, which is not to be regarded as limited by the detailed description of the preferred embodiment.

I claim:

1. A latching mechanism for the closure of a vehicle compartment or the like comprising a handle pivotally connected to said closure and adapted for manipulation between latching and unlatching positions, a torsion rod including a crank portion and a latch portion and pivotally mounted on said closure, a crank link connecting said handle and crank portion for swinging said latch portion between corresponding latching and unlatching positions on manipulation of said handle, a catch carried by said compartment and having an abutment with an aperture at one side thereof and including a cam surface within said aperture, said latch portion being adapted for entry in said aperture on closing said closure with said handle and latch portion in unlatching position and for engagement with said cam surface to actuate

said latch portion and handle into latching position, said latch portion being adapted to engage said abutment and avoid entry in said aperture with said handle and latch portion in latching position, and spring means arranged to urge said handle and latch portion towards latching position whereby an operator attempting to close said closure must retain said handle in unlatching position to effect entry of said latch portion in said aperture.

10 2. A latching mechanism according to claim 1 including a stop surface on said closure engageable by said crank link to determine the unlatching position of said handle.

3. A latching mechanism according to claim 1 wherein in said spring means comprises a coil spring concentric with said pivotal connection of said handle to said closure.

4. A latching mechanism for the closure of a vehicle compartment or the like, comprising a handle pivotally connected to said closure and adapted for manipulation between latching and unlatching positions, a torsion rod pivotally mounted on said closure, said torsion rod including a crank portion and a latch portion, a link pivotally connected at one end to said handle and at the other end to said crank portion, a catch carried by said compartment coacting with said latch portion, said catch having an abutment and an aperture the latter defining a cam surface for camming engagement with said latch portion, a stop surface on said closure engageable in the unlatching position of said handle with that portion of said link which is pivotally connected to said crank portion for determining the position of the latch portion with respect to the abutment and the aperture of said catch, and spring means biasing said handle toward latching position.

5. A latching mechanism according to claim 4 wherein in said stop surface on the closure allows said link-to-crank portion pivot to overcenter with respect to the link-to-handle pivot and torsion rod-to-closure pivot to releasably retain the latching mechanism in unlatched position upon release of the handle in its uppermost unlatched position so that the closure may be slam-latched without further manipulation of the handle.

6. A latching mechanism according to claim 4 wherein said spring means comprises a coil spring concentric with said pivotal connection of said handle to said closure.
